PAGE 2

FIG. 2

FIG. 4

FIG. 1 is a perspective view taken from the front and left side of a portable spraying unit showing my new design;

FIG. 2 is a perspective view taken from the front and right side thereof;

FIG. 3 is a right side elevational view thereof; and
FIG. 4 is a rear elevational view thereof.

The nozzle supply hose has been broken away in FIGS. 1, 3 and 4 to indicate indeterminate length.

I claim:

The ornamental design for a portable spraying unit, substantially as shown and described.
